US00D742411S

(12) **United States Design Patent**
Kim et al.

(10) **Patent No.:** US D742,411 S
(45) **Date of Patent:** ** Nov. 3, 2015

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventors: **Min Hyung Kim**, Seoul (KR);
PillKyoung Moon, Seoul (KR);
Changsoo Lee, Seoul (KR)

(73) Assignee: **Samsung Electronics Co., Ltd.**,
Suwon-si (KR)

(**) Term: **14 Years**

(21) Appl. No.: **29/459,426**

(22) Filed: **Jun. 28, 2013**

(30) **Foreign Application Priority Data**

Jan. 4, 2013 (KR) 30-2013-0000703

(51) **LOC (10) Cl.** **14-04**

(52) **U.S. Cl.**

USPC **D14/492**

(58) **Field of Classification Search**

USPC D14/487-495

CPC H04N 1/00424; G06F 3/04817

(57) **CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is an enlarged front view of the graphical user interface of FIG. 1.

The dash-dot-dash lines represent the bounds claimed design in all the FIGS. and form no part thereof; the dash-dot lines represent the display screen in FIG. 1 and form no part of the claimed design.

1 Claim, 2 Drawing Sheets

FIG. 1

FIG. 2
